ROTOR BRAKE AND SPINNER LEVER

Carl McDermott, Freehold, N. J.

Application October 3, 1944, Serial No. 557,044

3 Claims. (Cl. 171—76)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to improvements in switches.

In small generators, which are not self-starting and especially where the propelling energy is limited, some starting means is necessary to overcome the starting inertia. This is particularly true where a residual flux must be broken to start the generator.

It is, therefore, an object of the present invention to provide a means of starting small generators and the like.

It is another object to provide such a starting means which will also act as a brake when the generator is not in operation.

It is another object to provide such a means which may act as an "on-off" switch for an electrical generator or the like.

It is still another object to provide such a means which is compact and is simple and sure in operation and is inexpensive to manufacture.

Still other objects and uses will become clear from the following specification and claims and the appended drawings.

To illustrate the present invention, there will be described a switch for a spring rotated, self-generating flashlight. Said switch, in general, includes a lever pivoted at a central point thereof which, if swung in one direction, is urged into frictional engagement with the generator shaft and acts as a brake, but which, if swung in the opposite direction, gives the generator shaft an initial spin and then loses engagement with it so as to allow it to rotate freely.

In the drawings,

Figure 1 is a fragmentary longitudinal cross sectional view of a self-generating cylindrical flashlight, wherein a switch, embodying the present invention, is also shown in cross section, the lever being shown in its vertical position, midway between its "on" and "off" positions;

Figure 2 is a view, along the line 2—2 of Figure 1, the lever being shown at its "off" position in solid lines and at its "on" position in broken lines and the pivot pin and the spring pins being shown in section for clarity;

Figure 3 is a view similar to Figure 1 of a modified form of switch embodying the present invention, and;

Figure 4 is a view, along the line 4—4 of Figure 3, the lever being shown at its "on" position in solid lines and at its "off" position in broken lines.

2

Referring to the embodiment shown in Figures 1 and 2, a plate 11 is secured transversely within a cylindrical flashlight case 13. A generator shaft 15, concentrically disposed within said case 13, extends through an aperture 17 at the center of said plate 11 and is provided with a friction wheel 19 rigidly secured thereto, as by a key (not shown). Secured normal to said plate 11 is a pivot pin 23 which extends through a pivot hole 25 in a switch lever 27. The said pivot hole 25 is elongated so as to allow the lever 27 a limited lengthwise movement, in addition to its pivotal movement about said pin 23. One of the lower corners of the lever 27 is cut away to form a chamfer 29.

The lower friction surface 30 of the lever 27 may be fitted with a friction pad (not shown). The upper end of the lever 27 has a longitudinally disposed, threaded bore 31 into which is threadably fastened a screw 33. The head of said screw 33 is in the form of a knurled switch button 35. The screw 33 extends through an elongated slot 21 in the cylindrical case 13, the switch button 35 being positioned outside said case. The slot 21 is of a length to allow the lever 27 to pivot a predetermined distance as will be more clearly explained hereinafter. The lever 27 is provided with a notch 39 across its upper surface to slidably accommodate a spring 41 consisting of a length of piano wire. The ends of said spring 41 are bent under two spring pins 43 which are secured perpendicularly to the plate 11 aforementioned.

In operation of the device shown in Figures 1 and 2, the parts are normally in their "off" positions, as shown in solid lines in Figure 2. When so disposed, the spring 41 urges the lever 27 downwardly longitudinally so that the friction surface 30 is in frictional engagement with the friction wheel 19, thereby acting as a brake to prevent the said friction wheel, the generator shaft 15 and the generator (not shown) from rotating. The flashlight is then inoperative, or "off."

In order to switch to the "on" position, the switch button 35 is flipped to the left (as indicated by the arrow in Figure 2), to pivot the lever 27 about the pivot pin, whereupon the friction surface 30 causes the friction wheel 19 and the generator shaft 15 to spin in a clockwise direction (as indicated by the arrow in Figure 2). As the lever 27 is pivoted, it is urged downwardly by the spring 41 until the upper end of the pivot hole 25 hits the pivot pin 23, whereupon the friction surface 30 loses engagement with the friction wheel 19 and the generator shaft 15 is free to rotate.

To again switch to "off" position, the switch button 35 is flipped to the right to its first mentioned position, whereby the friction surface 38 again engages the friction wheel 18 and stops its rotation.

The modified switch, shown in Figures 3 and 4, is similar to the device in Figures 1 and 2, and similar parts bear similar numbers, except for the spring means, a coil spring 47 being substituted for the spring 41. In said modified switch the lever 27 is provided with a bore 45 which extends from the top of said lever almost, but not quite, to the bottom of said lever, and which crosses the pivot hole 28. The said bore 45 is threaded only through its upper portion to receive the screw 33. Within the said bore 45 and below the pivot pin 28 is a small coil spring 47, the upper end of which abuts the pivot pin 28. The operation of the modified device of Figures 3 and 4 is the same as that of the device of Figures 1 and 2, except that the coil spring 47 takes the place of the spring 41 to urge the lever 27 downwardly longitudinally so as to effect a good frictional engagement between the friction surface 38 and the friction wheel 18. The parts are shown in their "on" positions in solid lines. To switch to the "off" position, the switch button 35 would be flipped to the right (as indicated by the arrow in Figure 4), whereupon the parts would be in the positions shown in broken lines.

It will be understood that modifications may be made within the spirit of the present invention, and said invention is not limited to the embodiments shown in the drawings and described herein.

I claim:

1. An "on-off" control for a flashlight having a cylindrical case and a rotatable cylindrical generator member concentric with said case, comprising a pivot pin secured within said case, parallel to the axis of said generator member, and intermediate the case and the said member, an aperture through said case, a control lever extending through said aperture; a control button attached to one end of the lever outside said

case, a friction surface on the other end of the lever inside said case, a transverse pivot hole in said lever, said pivot hole having a greater diameter longitudinally of the lever and a lesser diameter athwart of the lever, said pivot pin being positioned in said pivot hole so that said lever may pivot about said pivot pin and may move longitudinally a limited distance, spring means to urge the lever longitudinally toward the generator member, said friction surface being frictionally engageable with the generator member during part of its pivotal movement, stop means to limit the pivotal motion of said lever in one direction so that the friction surface is in frictional engagement with the generator member at the end of its pivotal movement in that direction, 15 second stop means to limit the pivotal motion of said lever in the opposite direction so that the friction surface loses frictional engagement with the generator member at the end of its pivotal movement in that direction.

2. An "on-off" control as defined in claim 1, wherein the spring means is a length of spring wire.

25 3. An "on-off" control as defined in claim 1, wherein a longitudinally disposed bore extends part-way through said lever and interconnects with the pivot hole aforesaid, and the spring means is a coil spring disposed in said bore and is under compression between the pivot pin and one end of said bore.

CARL McDERMOTT.
